UNITED STATES PATENT OFFICE

HAROLD A. DAVIES, OF MONTEREY, CALIFORNIA

SAW HANDLE

Application filed July 8, 1931. Serial No. 549,521.

My invention relates to improvements in saw handles of the kind adapted to receive blades of different kinds; and the objects of my invention are to provide a metal handle that will not break readily should it drop a considerable distance such for instance as from one story to another in the construction of buildings, which is a frequent cause of breakage to wooden handles; to provide a handle which can be expeditiously molded, of such metal as an aluminum alloy preferably by die-casting whereby manufacturing costs are reduced; to provide a handle of light weight and convenient shape, comfortable to the hand of the user and provided with a fluted rest for the thumb of either a right or left handed user by means of which a better control of the saw is attained, which is highly desirable when sawing curves; to provide a ventilated construction which adds beauty to the shape of the handle and saves metal; to provide simple and efficient means to insert blades of different kinds and hold them securely in place; together with other objects and advantages which may hereafter appear, be pointed out particularly in the claims, and illustrated in the drawings here-
to attached and made part hereof, in which:—

Figure 1 is a side elevational view with a broken-away saw inserted.

Figure 2 is a front elevational view with the saw and clamping means removed.

Figure 3 is a top plan view with the saw removed.

Figure 4 is a section taken on the line IV—IV of Figure 1.

Figure 5 shows the clamping bolt.

Similar reference indicia refer to similar parts throughout the several views.

In carrying out my invention I provide the metal handle illustrated, comprising; the ellipsoidal opening 5 separated from the ventilating opening 6 by the wall 7 the forward curve 8 of which forms a convenient grasp for the fingers. The rear wall 9 fits the hollow of the hand and permits the thumb to rest in the fluted portion 10. The front portion 11 is suitably rounded and provided with the vertical medial slot 12 to accommodate the tank end of the blades. Said

portion is provided with the transverse locking-pin 13 adapted to coact with the clamping-bolt-B and the slot 15 of the saw to hold the saw in true alinement against vertical pressures, said slot being indicated in dotted lines in Figure 1. The bolt B well shown in Figure 5 has the screw-slot 16, the thread 17 adjacent the underside of the head 18, the plain portion 19 and the end thread 20 adapted to engage the lever-nut 21; the thread 17 being adapted to interengage complementary threads provided in the jaw 22.

It will be noted that the front wall 23 of the opening 5 forms a guard for the knuckles.

It will be further noted that the opening 6 is bounded by the arcuate wall 7, the substantially level base line 24 and the semicircular upper line 25 lightened by the cut-away 26 which enhances the appearance and saves metal.

I am aware that the prior patent art shows handles of this generic type, I therefore do not claim it broadly, but:—

I claim:—

1. As a new article of manufacture, a saw handle comprising a metal casting having a clamping means arranged to hold a saw, a guard wall partly bounding an ellipsoidal opening, an arcuate wall partitioning a ventilating opening from said former opening, a rear member rising from the lower wall of said arcuate opening to form a forwardly-extending rib terminating in a saw cleft, a flute on each side said rib, said flutes following the contour of the ellipsoidal opening substantially half way of the major axis of said ellipse.

2. In an article as specified in claim 1 having a ventilating opening, said opening being bounded by a substantially level lower outline, a semi-circular upper line and by curved side lines approximately in parallelism.

3. In an article as specified in claim 1 having a cleft to receive a saw, a clamp means coacting with a cross bolt and a cross pin to secure alinement and hold the saw in place.

In testimony whereof I affix my signature this 1st day of July, 1931.

HAROLD A. DAVIES. 100
